UNITED STATES PATENT OFFICE.

WILLIAM FULLARD, OF BURLINGTON, NEW JERSEY.

DEVICE FOR SMOKING MEATS.

1,280,009.

Specification of Letters Patent. Patented Sept. 24, 1918.

Application filed August 20, 1917. Serial No. 187,129.

To all whom it may concern:

Be it known that I, WILLIAM FULLARD, a citizen of the United States, residing at Burlington, in the county of Burlington, State of New Jersey, have invented a new and useful Device for Smoking Meats, of which the following is a specification.

My invention consists of a device for smoking meats or other articles wherein provision is made for subjecting the articles to heated fresh atmospheric air and smoke, thus effectively accomplishing the smoking, and avoiding the subjection of the articles to impure, confined or germ-infected air without being subjected to the products of combustion of the smoke-forming and air-heating devices employed, and vastly improving the quality and flavor thereof.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a vertical section on line 1—1 Fig. 2, of a device for smoking meats embodying my invention.

Fig. 2 represents a horizontal section thereof on line 2—2 Fig. 1.

Fig. 3 represents a vertical section on the line 3—3 Fig. 1.

Fig. 4 represents a vertical section of the lower part of the device on an enlarged scale.

Similar numerals of reference indicate corresponding parts in the figures.

Referring to the drawings.

1 designates a casing or what may be termed a smoke house, the same containing 40 the horizontally arranged pipes 2, and the rack bars 3 properly supported therein, and arranged in tiers, the bars having the meat supporting hooks 4 connected therewith.

The pipes 2 of each set of tiers are perforated and they are connected with the horizontally arranged smoke distributing pipes 5, said pipes 2 being staggered on said pipes 5.

The tiers of pipes 2 have their distributing pipes 5 connected with the vertically arranged pipe 6, said pipes 6 and 5 being in communication.

Connected with the pipe 6 preferably at the lower end thereof is the branch pipe 7, which is continuous of the coil 8, the latter comprising an air receiver being inclosed in

the chamber 9, and being disposed above the gas or other burner or stove 10 which is contained in the chamber 9.

The coil 8 is connected by the pipe 11 with the casing of the blower 12, power being communicated to the latter in any suitable manner, said casing being in communication with the atmosphere by the inlet pipe 13 whereby atmospheric air may be drawn into said casing and driven by the pipe 11 into the coil 8, wherein it is heated, in which condition it is driven through the pipe 7 into the vertically arranged pipe 6.

Connected with said pipe 6 adjacent to the branch pipe 7 is the branch pipe 14 with which said branch 7 is confluent at said pipe 6, and so together said branches are in communication with said pipe 6 as a common inlet to the interior of the smoke house. The pipe 14 is connected with the smoke producing box 15 and connects with the interior thereof. In said box is the spiral conveyer and agitator 16, which is adapted to be rotated by any suitable means, said box having also the hopper 17 for supplying saw-dust to said box 15, the outlet 18 for ashes and the cock or valve 19 for the admission of air. Below the box 15 is the gas or other burner or stove 20 whereby said box and its contents may be heated. Owing to said cock or valve 19, I am enabled to create a draft through the smoke box for effectively directing the smoke therefrom into the pipe 14.

The operation is as follows:

The box 15 is supplied with saw dust or other material employed for smoking meats, and the same is agitated by the conveyer 16 and fed from one end of the box to the other while it is subjected to the heated condition of the box, and so it is converted into smoke, which leaves the box and enters the branch pipe 14, and consequently the pipe 6. Meanwhile fresh atmospheric air is driven by the blower 12 into the coil 8, and from the latter into the branch pipe 7, and consequently into said pipe 6, whereby the smoke is ejected forcibly by said hot air driven from said branch 7 from the pipe 14 into said pipe 6, the hot air and smoke commingling and both together being injected into the pipe 6 and from thence into the distributing pipes 5, the perforated pipes 2 and casing 1 in jets filling said casing therewith so that the meats in the casing will be effectively and sanitarily smoked this being accomplished.

by the use of pure atmospheric air in heated condition in connection with the smoke, avoiding the impurities of confined air and radiated air and preventing the products of combustion of the burners or heaters 10 and 20 entering the casing or smoke house 1 and reaching the meat in the latter.

The ashes of the saw dust or material converted into smoke will be directed to the 10 outlet opening 18 and deposited in the pan or receptacle 21 provided for that purpose.

It is evident that articles of food other than meats may be smoked.

The casing is provided with the cock 22 15 which may be opened to permit when desired an upward draft of the smoke through the casing and to adjust the extent of said draft or cause the casing to be cleared entirely of smoke when the work is accomplished.

The casing 1 is provided with suitable doors 23 to permit access to the interior thereof, the same during the smoking operation being closed and held in such position by suitable means.

It will be seen that the material in the smoke-box to be converted into smoke does not have the products of combustion of the burner or stove 20 come in contact with the 30 same, as such products are applied to the exterior of said box, and the heater or stove 10 is on the exterior of the air container 8, so the products of combustion from both sources are not directed into the smoke 35 chamber or smoke house, whereby the articles in the smoke house are not tainted or affected by said products, while on the contrary, said articles are subjected to the combined action of pure fresh air and created 40 smoke in the smoke box, thus producing superior results in articles thoroughly smoking the articles in a sanitary manner, and imparting a fine flavor thereto.

Again, owing to the injection of hot atmospheric air into the smoke chamber, the articles subjected to the smoking action, especially in the case of fish, will be effectively dried, as well as smoked, and so said goods are well preserved and are not liable to rapid decay, or being otherwise impaired.

In some cases, the bars 3 are removably supported in the casing or house 1, and the stationary hooks 4 carried by the same, as shown in Fig. 1, or said bars may be stationarily connected with the frame or casing, whereby they form runways for the traveling hooks 4, as shown in Fig. 3, so as to adjust the position within the casing or house of the articles of food hung on said hooks.

Having thus described my invention what I claim as new and desire to secure by Letters Patent, is:

1. A smoke house, a box adapted to contain smoke-forming material, a heater for

said box on the exterior thereof, a container for atmospheric air, means for forcing the atmospheric air into said container and impelling it forcibly therefrom, a heater for said container on the exterior thereof, a smoke discharge pipe on said box, and a heated air discharge pipe on said container, said discharge pipes being adapted to open into said smoke house.

2. In a device for smoking articles, a smoke house, a box adapted to contain smoke forming material, a heater for said box, a container for atmospheric air, means for directing the atmospheric air into said container and impelling it forcibly therefrom, a heater for said container, a smoke discharge pipe on said box, a hot air discharge pipe on said container, and an inlet on said smoke house, said discharge pipes being common to said inlet whereby the hot air under pressure serves to inject the smoke from the box in which it is formed into said inlet, commingled with the hot air, the products of combustion being removed from communication with said smoke house.

3. A smoke house, means for forming smoke of a suitable material, a heater for said means, an air container, a member for forcibly directing atmospheric air into said container, and conveyers for the hot air and smoke connected respectively with said means and conveyer to the smoke house, the latter having a common inlet for said conveyers.

4. A smoke house, a perforated pipe therein, a container for atmospheric air, a heater for said container, a device for supplying said container with the atmospheric air and forcibly impelling it to the smoke house, and a conveyer for the heated air from said container connectible with said perforated pipe.

5. A smoke house, a box adapted to contain a smoke-forming material, a heater for said box on the exterior thereof, a smoke discharge pipe connected with said box and the smoke-house, an air container, a blower adapted to receive fresh atmospheric air and impel it forcibly into said container and therefrom, a heater for said container on the exterior thereof, and a discharge pipe connected with said container and the smoke house, the latter having an inlet into the interior thereof, said discharge pipes being in communication with said inlet whereby the discharged heated air under pressure serves as an ejector for the smoke from the box in which it is formed, and for said smoke and air together into the smoke house.

6. A smoke house, a perforated pipe therein, a box adapted to contain smoke-forming material, a device for exteriorly heating said box, a container for atmospheric air, a device for forcing the atmospheric air into said container and impelling it therefrom, a device for exteriorly heating said con-

tainer, a pipe connected with the latter for discharging the heated air therefrom, a pipe connected with said box for discharging the resultant smoke therefrom, and a pipe in 5 the smoke house in communication with said discharge pipes and with said perforated pipe.

7. A casing forming a house adapted to receive the article to be smoked, a box adapted to contain smoke-producing material, and an agent for externally heating said box, whereby said material may be converted into smoke while being removed from the direct 10 action of the products of combustion of said

heating agent, and a container for atmospheric air, a device for forcing the atmospheric air into said container and impelling it forcibly therefrom into said casing, and a device for externally heating said container whereby the products of combustion 15 are re-employed for heating said device are removed from the heated air and its entrance into said casing with the resultant smoke. 20
